ELECTRIC SWITCH COMBINED WITH FLUID CONTROL VALVE

Filed Aug. 25, 1950

UNITED STATES PATENT OFFICE

2,596,505

ELECTRIC SWITCH COMBINED WITH FLUID
CONTROL VALVE

John Pacifico, Staten Island, N. Y.

Application August 25, 1950, Serial No. 181,339

2 Claims. (Cl. 200—53)

1

This invention relates to an electrical gas stove pilot arrangement.

It is an object of the present invention to provide an electrical gas stove pilot arrangement wherein automatically as the gas valve is turned by a special button arrangement disposed thereon as an attachment therefor, an electric circuit is closed to operate a pilot and to cause a flash between the points thereof, and wherein upon release of the gas valve, the pilot circuit is automatically broken.

Other objects of the present invention are to provide an electrical pilot arrangement for gas stoves which is of simple construction, inexpensive to manufacture, has a minimum number of parts, easy to install upon the gas stove, compact, reliable and efficient in operation.

For other objects and for a better understanding of the invention, reference may be had to the following detailed description taken in connection with the accompanying drawing, in which

Fig. 1 is a top plan view of a gas stove with a diagrammatic showing of the wiring and of the operating switch member connected to the gas valves.

Fig. 2 is an enlarged vertical sectional view taken on line 2—2 of Fig. 1.

Fig. 3 is an enlarged plan view of the valve with the operating switch button connected thereto and shown in section.

Fig. 4 is a transverse sectional view taken on line 4—4 of Fig. 3 with the operating switch member out of contact with the gas valve handle.

Fig. 5 is a view similar to Fig. 4, but with pressure applied to the operating switch member so that contact is effected through the valve.

Referring now to the figures, 10 represents a gas range having ring burners 11 and an oven burner 12. This gas range is supplied from a pipe 13 with gas and this pipe is connected with a control pipe 14 that extends across the front of the gas range.

In this control pipe 14 there are a plurality of laterally spaced valve elements 15 for controlling the supply of gas to the individual and respective burners 11 and 12. This gas valve is constituted of the standard parts and can be turned on or off or to positions therebetween so that the flow of the gas can be adjusted to the different heating requirements. Valve 15 has a rotatable member 16 therewithin that projects outwardly and carries a hand knob 17 with an axially extending projection 18 thereon.

According to the present invention, there is attached to the knob 17 a slidably fitted knob 19

2

having enlarged opening 21 therein receiving the projection 18. Accordingly, there is a loose fit of the knob 19 with the projection 18. Between this knob 19 and the knob 17 there are connected a plurality of balancing springs 22 which will urge the knob 19 toward a neutral position so that the projection 18 is out of engagement with a contact 23, as shown in Fig. 4. Contact 23 is made secure upon the knob 19 by a screw 24. As the knob 19 is turned, the contact 23 is engaged in the manner as shown in Fig. 5 with the projection 18 whereby to close the electric circuit 25. This circuit 25 includes primary winding 26, plug 27 which may be secured to any wall receptacle, wire 28 leading from the plug 27 is grounded on the gas range 10.

The transformer also has a secondary circuit 29 that includes winding 31, oven spark points 32 and 33 lying adjacent oven heater element 12 and spark points 36 and 37 for the range 11. The spark points 36 are confined within a round receptacle 38, Fig. 2, which has sleeves 39 and 40 extending in opposite directions toward the respective gas rings 11 of a pair. As any one of the gas valves are turned, a spark will jump the points so as to ignite any gas which may linger near to them.

Over each pair of rings 11 is a plate 41 having holes 42 therein through which flames from the gas rings 11 project. Brackets 43 are connected to the top of the range and the plate 41 is secured to the upper ends of these brackets by fastening screws 44. The brackets are connected to the top of the range by fastening screws 45. The gas rings 11 are supported upon insulating blocks 46. The brackets 43 may also be of insulating material. The receptacle 38 is supported upon an insulating block 47 and the knobs 19 are also of insulating material so that the user of the gas range does not come in contact with the electrical circuit.

It should now be apparent that there has been provided an electrical arrangement for igniting gas ranges which is simple to construct and wherein automatically by the simple turning of the knob which turns the valve, the ignition of the gas burner is effected. It will be seen that this arrangement merely requires the attachment to the valves of a simple insulating knob and the springs 22 on the standard gas valve knob 17. Small holes can be drilled into the knob 17 to receive the ends of the respective springs 22 in a tight fitting manner. The springs 22 automatically return the knob 19 to

a neutral position, as shown in Figs. 3 and 4, with the contact 23 free of the projection 18.

While various changes may be made in the detail construction, it shall be understood that such changes shall be within the spirit and scope of the present invention as defined by the appended claims.

I claim:

1. In combination, a fluid control valve having a turn knob, an electric switch turn knob, one of said knobs having a projection thereon, the other of said knobs having a recess therein for receiving the projection, said recess being larger than the projection to allow limited relative movement between said other of said knobs and said projection, balance spring means connecting said knobs and normally maintaining the projection positioned in said other knob, said other knob having a contact element engageable with the projection when one of said knobs is turned to turn the other of said knobs. 20

2. In combination, a fluid control valve having a turn knob with a projection thereon, an electric switch turn knob having a recess there-

in for receiving the projection upon the turn knob of the valve, said recess being substantially larger than the projection to allow limited relative movement between the switch turn knob and the projection, balance spring means connecting the switch turn knob with the turn knob of the valve and normally maintaining the projection positioned in the switch turn knob, said switch turn knob having a contact element engageable with the projection when the switch turn knob is turned to turn the valve knob.

JOHN PACIFICO.
